(57) **CLAIM**

The ornamental design for a dinosaur toy as shown and described.

DESCRIPTION

FIG. 1 is a front elevation view of a dinosaur toy showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view of a dinosaur toy showing the claimed design.

The broken lines shown in the drawings and the ghosting areas within the broken lines show portions of the article that form no part of the claimed design.

1 Claim, 7 Drawing Sheets
